(57) **CLAIM**

The ornamental design for a cooler control, as shown and described.

DESCRIPTION

FIG. 1 is a perspective view of a cooler control showing my new design;

FIG. 2 is a front elevational view thereof;

FIG. 3 is a top elevational view thereof;

FIG. 4 is a right side elevational view thereof, the left side elevational view being a mirror image of the right side; and, FIG. 5 is an enlarged partial elevational view thereof showing numerals and descriptive matter for purpose of illustration only and forming no part of the claimed design.

The broken line showing of the environment is for illustrative purpose only and forms no part of the claimed design.
